(57) **CLAIM**

The ornamental design for a casing with memory card storage, as shown and described.

DESCRIPTION

FIG. 1 is an isometric view of a casing with memory card storage;

FIG. 2 is an exploded isometric view thereof, the broken line showing a memory card is for illustrative purposes only and forms no part of the claimed design;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top plan view thereof; and,

FIG. 8 is a bottom plan view thereof.
